(57) **CLAIM**

The ornamental design for a device privacy cover, as shown and described.

DESCRIPTION

FIG. 1 is a top, front, right-side perspective view of a device privacy cover showing our new design;

FIG. 2 is a top, back, left-side perspective view thereof;

FIG. 3 is a bottom, back, left-side perspective view thereof;

FIG. 4 is a front view thereof;

FIG. 5 is a back view thereof;

FIG. 6 is a right-side view thereof;

FIG. 7 is a left-side view thereof;

FIG. 8 is a top view thereof;

FIG. 9 is a bottom view thereof;

FIG. 10 is a top, front, right-side perspective view thereof in a position of use with a device shown in broken lines;

FIG. 11 is a bottom, back, left-side perspective view thereof in a position of use with a device shown in broken lines;

FIG. 12 is a top, right-side perspective view thereof in a position of use with a device shown in broken lines;

FIG. 13 is a bottom, left-side perspective view thereof in a position of use with a device shown in broken lines;

FIG. 14 is a top, left-side perspective view thereof in a position of use with a device shown in broken lines; and,

FIG. 15 is a bottom, right-side perspective view thereof in a position of use with a device shown in broken lines.

The dashed broken lines depict portions of the device privacy cover and environmental context of the device privacy cover that form no part of the claimed design.

1 Claim, 15 Drawing Sheets
